Primary Examiner — Jasmine Mlinarcik

(74) *Attorney, Agent, or Firm* — CANTOR COLBURN LLP

(57) **CLAIM**

The ornamental design for underwear, as shown and described.

DESCRIPTION

FIG. 1 is a front elevation view of the underwear showing our new design;

FIG. 2 is a rear elevation view thereof;

FIG. 3 is a right-side elevation view thereof;

FIG. 4 is a left-side elevation view thereof;

FIG. 5 is a top plan view thereof; and,

FIG. 6 is a bottom plan view thereof.

The broken dash lines in the figures depict portions of the underwear that form no part of the claimed invention. Neither the portions of the underwear shown in broken dash lines nor the broken dash lines themselves form any part of the claimed invention.

1 Claim, 3 Drawing Sheets
